UNITED STATES PATENT OFFICE.

WALTER H. WAKEFIELD, OF WORCESTER, MASSACHUSETTS.

TUBE FRAME FOR AXMINSTER LOOMS.

Application filed February 15, 1926. Serial No. 88,187.

This invention relates to improvements in tube frames such as are employed on Axminster looms and it is the general object of the invention to provide an improved 5 ear or hanger for the tube frame to cooperate with a stop motion effective to stop the loom when either end of the tube frame fails to be released from the transporting chain. Axminster looms employ a series of tube 10 frames which are moved successively to weaving position by means of transporting chains and said tube frames are held to the chain by means of hook devices movably mounted on the tube frame. A pair of 15 clutches move toward the tube frame to release the same from the chain and thereafter move the tube frame to tuft position, but it occasionally happens that although the 20 clutches may operate properly yet a tube may fail to be released from the chain due to some defect of the tube frame itself and it is desirable to stop the loom under such 25 conditions to prevent an empty pick in the fabric. A device for accomplishing this result is shown in Patent No. 1,546,685, to Streimer, said patent showing a rigid latch pivoted to the tube frame hanger and having a projection extending under the hook engaging portion of the clutch so that should 30 the tube frame fail to be released the clutch will be held in raised position and devices operated in timed relation with the clutch will act to stop the loom. The hook as shown in said patent is a difficult one to 35 make because of the projection and it is an important object of my invention to provide a hook formed from flat stock to cooperate with a tube frame hanger a portion 40 of which is struck out to receive the hook and extends beyond the plane of the hook to cooperate with the stopping mechanism of the loom.

It is a further object of the invention to employ the general construction shown in 45 Patent No. 1,462,520, to Ryon but to use material wasted in Ryon to accomplish the stopping set forth in the Streimer patent without the expensive hook of the latter construction.

With these and other objects in view 50 which will appear as the description proceeds, my invention resides in the combination and arrangement of parts hereinafter described and set forth in the claims.

In the accompanying drawings wherein I

have shown a convenient embodiment of my invention:—

Fig. 1 is an end elevation of the tube frame releasing arm of an Axminster loom, taken from the right hand end of the loom, 60 certain parts being in section,

Fig. 2 is an enlarged end view of a tube frame looking in the direction in which Fig. 1 is taken,

Fig. 3 is a vertical section on line 3—3 of 65 Fig. 2 showing the parts in normal position with the tube frame supported by the transporting chain,

Fig. 4 is a horizontal detail section on line 70 4—4 of Fig. 3 showing the releasing clutch in operative position,

Fig. 5 is a view similar to Fig. 3 but showing the clutch moved downwardly and supported by a portion of the tube frame hanger in such position as will stop the 75 loom,

Fig. 6 is a fragmentary end elevation of the lower portion of the hanger of the tube frame with the hook removed, and

Fig. 7 is a section on line 7—7 of Fig. 6. 80

Referring to the drawings it will be seen that I have provided a tubular member 10 formed of a hollow, rectangular, metallic pipe to which is secured an ear or hanger 11 having an upwardly extending spool bearing 85 arm 12 to support the gudgeon 13 of a yarn spool 14. Said spool bearing is provided with an arm 15 extending into the tubular member 10 and held therein as by screws 16. A second chain engaging member 17 has an 90 upwardly extending tongue 18 which extends between the inner and outer links 19 and 20, respectively, of a transporting chain and said member 17 is provided with a horizontal arm 21 secured to the bottom of 95 the tubular member by screw 22.

A rigid chain engaging hook latch 23 has formed thereon a hooked end 24 to engage the link 19 of the transporting chain and is provided with a bent portion 25 which extends through a slot 26 formed in the bottom of the member 17, the inner end of the hook being bent upwardly from the portion 25 and extending horizontally as at 27 adjacent to the arm 15. A compression spring 100 28 is located between the arms 21 and 27 and serves normally to push the hook 23 outwardly into holding engagement with the link 19 as shown in Fig. 3. The portion of the member 17 lying immediately under the 110

rounded part 25 of the hook latch 23 is formed as a tongue 29 on the member 17, said tongue being bent outwardly when the hook is being inserted and then being bent back into the position shown in Figs. 3 and 5 after the hook has been inserted in place. The matter thus far described is substantially the same as that set forth in Ryon's aforesaid Patent No. 1,462,520.

10 In said patent to Ryon the tongue 29 is cut off at the top portion thereof to make room for the latch 23 but in carrying out my invention I bend the upper end of the tongue 29 outwardly as shown at 40 so that 15 the same will extend beyond the plane of the outer face of the latch 23. This latter result may be given further effect by forming the tongue 29 with an upwardly extending lug 41 of less width than the slot 26 so 20 that the latch 23 will have holding engagement with the upper portion of the slot 26 below the recess 42 which remains after the lug 41 has been struck out.

The tube frame formed as herein described is adapted to cooperate with loom stopping mechanism of the type set forth in the aforesaid Streimer patent and a portion of which is shown in Fig. 1. As shown arm 50 moves about pivot 51 from the full 25 line raised position to the dotted line lowered position by actuating rod 52 which is lowered at the proper time in the operation of the loom to move the tube frame to tuft forming position. As the arm 50 descends it will depress a rod 53 which operates 30 through mechanism not shown to prevent the stopping of the loom, but should the arm 50 be held in raised position rod 53 will not be depressed and the stopping mechanism 35 will operate to arrest the loom.

The connection between the arm 50 and the chain which serves to hold said arm 50 in raised position comprises a lever 54 pivoted to the arm as at 55 and having mounted 40 thereon a clutch 56 which swings about a stud 57 on the lever 54 under influence of rod 58. The clutch 56 is provided with vertically extending flared wings 59 and a bottom wing 60. The upright body of the 45 clutch is provided with a vertical groove or recess 61 located between surfaces 62 which engage the member 17, the recess receiving the projecting end 40 of the tongue 29. Adjustable screw 63 is mounted in the upper 50 part of the clutch 56 and extends slightly into the upper portion of the recess 61 and normally engages the latch 23 as the clutch is moved inwardly from the position shown in Fig. 3 to that shown in Fig. 4.

55 Under normal conditions when the clutch moves toward the tube frame the hook 23 will be released from the transporting chain and the tube frame will be supported on the lower wing 60 and guided as to vertical 60 position by the vertical wings 69. The walls

62 will press against the member 17 and the hook member will lie in the recess 61 in a manner which is old in the art. As the rod 52 moves downwardly the tube frame will move to tuft forming position. Should an accident happen to the hook, however, and the same be bent to some such a position as shown in Fig. 5, it will not be entirely free from the transporting chain and will be held in raised position thereby so that as the clutch 56 moves downwardly the stud 63 will engage the outwardly bent end of tongue 29 as shown in Fig. 5 and rod 53 will be permitted to remain in raised position to stop the loom.

65 From the foregoing it will be seen that I have provided a very simple means for stopping an Axminster loom which permits the construction of a rigid latch from flat stock and furthermore permits the use of material which would otherwise be wasted simply by bending said material outwardly to lie in the path of the stud 63. It will also be seen that the projecting end of the tongue 29 extends into the recess 61 and lies vertically under the stud so that neither the stud nor the tongue interferes with the proper contact between the vertical walls 62 and the member 17.

70 Having thus described my invention it will be apparent that changes and modifications may be made therein without departing from the spirit and scope of the invention, and I do not wish to be limited to the details herein disclosed but what I claim is:—

75 1. In a tube frame for a loom having a downwardly moving tube frame supporting member to cooperate with stopping mechanism and a transporting chain, a chain engaging element secured to the tube frame, a chain engaging hook member having pivotal connection with the element and extending through said element, said element having a portion thereof under the hook member to extend beyond the outer face of said hook member for engagement with a portion of the member normally operative to move the tube frame to tuft forming position.

80 2. In a tube frame for a loom having a downwardly moving tube frame supporting member to cooperate with stopping mechanism and a transporting chain, a chain engaging element secured to the tube frame, a hook member having pivotal connection with the element and positioned to engage the chain, and a tongue struck from the element to define the space through which the hook member extends, said tongue extending beyond the hook member to lie vertically under a portion of the means to move the tube frame to tuft forming position.

85 3. In a tube frame for a loom having a downwardly moving tube frame supporting

- member to cooperate with stopping mechanism and a transporting chain, a chain engaging element, a hook member for the chain having pivotal connection with the element,
5 a portion of the element being bent outwardly beyond the hook member to form an opening through the element for the passage of the hook member, said portion being bent outwardly beyond said hook member for engagement with a part of the means 10 which normally moves the tube frame to tuft forming position.

In testimony whereof I have hereunto affixed my signature.

WALTER H. WAKEFIELD.

Certificate of Correction.

It is hereby certified that Letters Patent No. 1,597,938, granted August 31, 1926, upon the application of Walter H. Wakefield, of Worcester, Massachusetts, for an improvement in "Tube Frames for Axminster Looms," were erroneously issued to the inventor, said Wakefield, as owner of said invention, whereas said Letters Patent should have been issued to *Crompton & Knowles Loom Works, of Worcester, Massachusetts, a corporation of Massachusetts*, said corporation being owner of the entire interest in said invention, as shown by the records of assignments in this office; and that the said Letters Patent should be read with this correction therein that the same may conform to the record of the case in the Patent Office.

Signed and sealed this 5th day of October, A. D. 1926.

[SEAL.]

M. J. MOORE,
Acting Commissioner of Patents.
